[57] CLAIM

The ornamental design for a cabinet, as shown and described.

DESCRIPTION

FIG. 1 is a perspective view of a cabinet showing our new design;

FIG. 2 is a front elevational view thereof;

FIG. 3 is a rear elevational view thereof;

FIG. 4 is a right side elevational view thereof, of which the left side elevational view is a mirror image thereof;

FIG. 5 is a top plan view thereof;

FIG. 6 is a perspective view of a second embodiment of cabinet shown in FIG. 1;

FIG. 7 is a front elevational view thereof;

FIG. 8 is a rear elevational view thereof;

FIG. 9 is a right side elevational view, the left side being a mirror image thereof,

FIG. 10 is a top plan view thereof,

FIG. 11 is a perspective view of a third embodiment of the cabinet shown in FIG. 1;

FIG. 12 is a front elevational view thereof;

FIG. 13 is a rear elevational view thereof;

FIG. 14 is a right side elevational view, the left side being a mirror image thereof; and,

FIG. 15 is a top plan view thereof.
